Primary Examiner — Patricia A Palasik

(74) *Attorney, Agent, or Firm* — Perilla Knox & Hildebrandt LLP; Kenneth A. Knox

(57) **CLAIM**

The ornamental design for a dust box for cleaning robot as shown and described.

DESCRIPTION

1.1 : Front

1.2 : Back

1.3 : Left

1.4 : Right

1.5 : Top

1.6 : Bottom

1.7 : Perspective

1.8 : Perspective

1.9 : Perspective

2.1 : Front

2.2 : Back

2.3 : Left

2.4 : Right

2.5 : Top

2.6 : Bottom

2.7 : Perspective

2.8 : Perspective

2.9 : Perspective

1.1 is a front view of a first dust box for cleaning robot; **1.2** is a back view thereof; **1.3** is a left view thereof; **1.4** is a right view thereof; **1.5** is a top view thereof; **1.6** is a bottom view thereof; **1.7** to **1.9** are three perspective views thereof; **2.1** is a front view of a second dust box for cleaning robot; **2.2** is a back view thereof; **2.3** is a left view thereof; **2.4** is a right

(Continued)

view thereof; **2.5** is a top view thereof; **2.6** is a bottom view thereof; **2.7** to **2.9** are three perspective views thereof.

1 Claim, 18 Drawing Sheets
